(57) **CLAIM**

The ornamental design for a handheld skincare device, as shown and described.

DESCRIPTION

FIG. 1 illustrates a front perspective view of a handheld skincare device;

FIG. 2 illustrates a bottom perspective view of the handheld skincare device thereof;

FIG. 3 illustrates a front view of the handheld skincare device thereof;

FIG. 4 illustrates a back view of the handheld skincare device thereof;

FIG. 5 illustrates a left side view of the handheld skincare device thereof;

FIG. 6 illustrates a right side view of the handheld skincare device thereof;

FIG. 7 illustrates a top view of the handheld skincare device thereof; and,

FIG. 8 illustrates a bottom view of the handheld skincare device thereof.

The broken lines shown in the drawings are for the purpose of illustrating portions of the handheld skincare device, which form no part of the claimed design.
